ROBERT C. HOPKINS, OF ALLIANCE, OHIO

OIL AND GAS FURNACE

Application filed October 9, 1930. Serial No. 487,473.

The invention relates to heating furnaces which are preferably oil fired, and more particularly to the furnace wall arrangement and construction at and adjacent the fuel burners, of which there are always at least two.

It is most desirable in heating furnaces, which for the purpose of description and illustration may be of the drop forge type, 10 such as used for heating blanks for forging, having the usual hearth, side wall and roof arrangement, to utilize the blast issuing from the heating burner to induce a corresponding flow of hot gases in the furnace, and to 15 train the hot gases in the blast for preheating the air and fuel constituting the blast, just previously to and during combustion of the fuel for obtaining complete combustion of the fuel. Single burner furnaces have 20 been operated in this manner to obtain a flow of hot gases in the furnace induced by the action of the blast, which hot gases mix with the blast for preheating the same.

Such operation of single burner furnaces 25 has in one case required the provision of one or more passageways leading from a part of the heating chamber remote from the burner, back to the burner port where the action of the blast induces a flow of hot gases in the 30 passageways causing a mixing of the hot gases with the blast at and adjacent the burner port.

However, when these passageways are 35 small in cross-sectional area, the flow of hot gases may often be negligible due to friction losses, particularly when the passageways must traverse a circuitous route from a portion of the heating chamber remote from the burner back to the burner.

On the other hand, when the passageways 40 are sufficiently large enough so that friction losses are negligible and so that a substantial flow of hot gasses is present therein, a substantial amount of heat is given up from the hot gases to the passageway walls, with the 45 result that, although more efficient combustion may take place, the heat efficiency of the furnace is decreased because a certain amount of the heat has not been usefully used to heat the material in the furnace, but has been uselessly expended in heating the walls of the

passageway. For these reasons such passageway type furnaces have defeated the purposes for which they were intended and are inefficient.

Single burner furnaces have in another case 55 been designed to accomplish a mixing of hot gases with the burner blast by utilizing a quite complicated design of reverberatory heating chamber wherein the gases and blast churn round and round and substantially complete combustion is procured. However, the heating effect on the material in the furnace resulting from the intense heat of radiation of fuel particles at the instant of combustion is lost 60 in this type of furnace because combustion takes place in the adjacent reverberatory pre-heating chamber, while the heating of the material in the furnace proper is accomplished by the hot gases issuing from the pre-heating chamber.

Thus the heating efficiency of this last referred to type of furnace is relatively low notwithstanding the fact that substantially complete combustion has taken place.

In any event, the furnace construction of 75 each of the two described types of single burner furnaces is very expensive due to the provision of return passageways or flues or of complicatedly designed reverberatory pre-heating chamber.

It is therefore one of the objects of the present invention to provide a furnace and burner construction for heating furnaces in which complete combustion will take place, accompanied by a relatively high heating efficiency. 85

A further object of the present invention is to provide a furnace construction in which the burner blast will entrain hot gases from the heating chamber both by induction and by a direct pressure flow of the hot gases, for 90 preheating the blast to obtain complete combustion.

A further object of the present invention is to provide a furnace construction in which the air and fuel blast from the heating burner will be surrounded by a shield or casing of hot previously burned gases so as to interpose a layer or stratum of inert hot gases between the fire stream and the material being heated in the furnace.

A further object of the present invention is to provide a furnace construction in which combustion of the fuel takes place substantially entirely within the furnace heating chamber so that the material in the furnace will be exposed to the intense heat of radiation from the fuel particles at the instant of combustion.

And finally, it is an object of the present invention to provide a furnace construction for accomplishing all of the above purposes which has an extremely simple design and which will be very inexpensive to construct and maintain.

These and other objects may be attained by providing a furnace construction, a preferred embodiment of which is shown in the drawings and hereinafter described in detail, which may be stated in general terms as including a plurality of burner ports located at opposing portions of the furnace, a fuel burner located at each of the ports, the longitudinal axis of each of the burners being offset one from another, walls forming a hot-gas chamber adjacent each burner port, flame ports communicating between each hot-gas chamber and heating chamber in alignment with the respective burner ports, and hot-gas ports communicating between the heating chamber and the hot-gas chamber adjacent one burner and located in the path of the flame issuing from another burner.

The improved furnace construction is shown in the accompanying drawings, in which:

Figure 1 is a plan sectional view of the improved furnace taken on the line 1—1, Fig. 2; and

Fig. 2 is an elevation section of the improved furnace taken on the line 2—2, Fig. 1.

Similar numerals refer to similar parts throughout the drawings.

A heating furnace is indicated generally at 3, and for the purposes of illustration is of a usual drop forge type, and consists of a hearth wall 4, a rear wall 5, a front wall 6 provided with an opening 7 for introducing blanks for forging or other material to be heated into the furnace, a roof 8 and end walls 9. If desired any usual and well known form of door may be provided for the opening 7, although ordinarily none is necessary.

Partition walls 10 and 10a are provided adjacent to and spaced from the end walls 9 and form therewith hot-gas chambers indicated at 11 and 11a. One of the end walls 9 is provided with a burner port 12 spaced preferably intermediately between the hearth 4 and roof 8 and located nearer the front wall 6 than the rear wall 5, while a second burner port 13 is provided in the other end wall 9 spaced intermediately between the roof and hearth and located nearer to the rear wall 5 than the front wall 6.

Fuel burners 14 and 14a are provided at the

burner ports 12 and 13, and each burner has a fuel line connection 15, and an air line connection 16, which are connected with suitable sources of fuel and air under pressure, not shown. Thus, the axis of the fuel burner 14 is laterally offset from the axis of the fuel burner 14a.

The partition walls 10 and 10a have provided therein the enlarged openings or flame ports 17 and 17a, respectively, the flame port 17 being located in alignment with the burner port 12 and burner 14, and the flame port 17a being located in alignment with the burner port 13 and burner 14a. The flame ports 17 and 17a communicate between the hot-gas chambers 11 and 11a, respectively, and the heating chamber indicated generally at 18.

The partition walls 10 and 10a are also provided with hot-gas ports 19 and 19a, respectively, which communicate between the chambers 11 and 11a, respectively, and the heating chamber 18; the gas port 19 being located in the path of the flame issuing from the burner 14a, and the gas port 19a being located in the path of the flame issuing from the burner 14.

In the operation of the furnace, air and fuel, which may be oil, issues in a blast from the burner 14, across the chamber 11, through the flame opening 17, and into the heating chamber 18 wherein the material to be heated is located.

Meanwhile combustion of the fuel takes place and the flame and hot gases of combustion with the pressure of the blast behind them travel in the direction of the arrows shown in the drawing and enter the hot-gas port 19a into the hot-gas chamber 11a. The fuel and air blast from the burner 14a induces a flow of hot gases from the chamber 11a outward through the flame port 17a so that the hot gases preheat the fuel and air and insure complete combustion and at the same time envelop the fuel and air so as to interpose a layer of hot inert burned gases between the fire stream and the material being heated in the furnace.

At the same time, the flame from the burner 14a enters the hot-gas port 19 and passes into the hot-gas chamber 11 by the pressure of the blast and the hot gases in the chamber 11 are entrained by and surround the blast issuing from the burner 14.

Accordingly, complete combustion takes place in the furnace chamber with an accompanying high heating efficiency and the furnace construction is of simple design and inexpensive to construct and maintain.

It is pointed out that the fuel utilized may not necessarily be oil, but may be gas, tar, or other similar combustible fuel.

Likewise, it is not necessary for carrying out the purposes of the present invention that the furnace be rectangular as shown, but the same may be round or square.

Moreover, a proper operation of the fur-

nace for carrying out the present invention requires at least two burners and associated burner ports, flame ports, hot-gas chambers and hot-gas ports, but the purposes of the 5 present invention may be carried out equally as well by utilizing more than two burners with their associated ports and chambers so long as the gas port of one chamber is in the path of the flame issuing from another flame 10 port in alignment with another burner and burner port.

I claim:

1. In furnace wall and heating chamber construction a plurality of partition walls 15 spaced from the furnace walls to form hot-gas chambers, there being a burner port in the furnace walls communicating with each hot-gas chamber, the axes of the burner ports being offset from one another, there being a 20 flame port in each partition wall communicating between the respective hot-gas chamber and the furnace heating chamber and located in alignment with the adjacent burner port, and there being a hot-gas port in each 25 partition wall communicating between the respective hot-gas chamber and furnace heating chamber and located in alignment with the flame port of another hot-gas chamber.

2. In furnace construction including walls 30 forming a heating chamber, walls spaced from the furnace chamber walls to form two opposed hot-gas chambers, there being burner ports in said spaced walls and a fuel burner for each burner port, the axis of one burner 35 being offset from the axis of the other burner, there being a flame port communicating between each hot-gas chamber and the heating chamber and located in alignment with the respective burner, and there being a hot-gas 40 port communicating between each hot-gas chamber and the heating chamber and located in the path of the flame issuing from the opposed burner.

3. Furnace construction including walls 45 having a plurality of burner ports formed therein and located at opposing portions of the furnace, a fuel burner located at each of the ports, the longitudinal axis of each of the burners being offset from the others, walls 50 forming a hot-gas chamber adjacent each burner port, there being flame ports communicating between each hot-gas chamber and the furnace heating chamber located in alignment with the respective burner ports, 55 and a hot-gas port communicating between the heating chamber and each hot-gas chamber located adjacent one burner and in the path of the flame issuing from another burner.

60 4. Furnace construction including a plurality of burners, walls forming a heating chamber and a hot-gas chamber adjacent each burner, there being a burner port to each hot-gas chamber and a flame port communicating 65 between each hot-gas chamber and the heat-

ing chamber, said ports being aligned with their respective burners and offset with respect to other ports, and there being a hot-gas port for each hot-gas chamber located in the path of the flame issuing from a burner 70 adjacent another hot-gas chamber.

In testimony that I claim the above, I have hereunto subscribed my name.
